Primary Examiner — Angela J Lee(74) *Attorney, Agent, or Firm* — Leason Ellis LLP(57) **CLAIM**

The ornamental design for a rising platform, as shown and described.

DESCRIPTION

FIG. 1 is a perspective view of a rising platform having a top surface according to a first embodiment of our new design in a first position;

FIG. 2 is a perspective view of the rising platform according to the first embodiment in a second position which is raised and rotated relative to the first position;

FIG. 3 is top plan view of FIG. 2;

FIG. 4 is one side view of FIG. 3; and,

FIG. 5 is a second side view taken 180 degrees from FIG. 4. The dash-dash broken lines illustrate environmental structure and form no part of the claimed design.
